DESIGN FOR AN APRON

Emma Bertha Gooch, Valparaiso, Ind., assignor
to Vernon L. Philley, Valparaiso, Ind.

Application June 27, 1934, Serial No. 52,358

Term of patent 7 years

To all whom it may concern:—

Be it known that I, Emma Bertha Gooch, a citizen of the United States, residing at Valparaiso, in the county of Porter and State of Indiana, have invented a new, original, and ornamental Design for an Apron, of which the following is a specification, reference being had to the accompanying drawing, forming part thereof.

The design resides in an apron made of contrasting materials with a heart shaped pocket thereon and a larger heart inserted upside down in the middle of the lowest portion of the apron. Its curves correspond with the scalloped border insertion that extends upward at each edge. The

several parts are in contrast with each other and darker outlines formed of binding completes the ensemble.

Figure 1 is an elevation of the apron with all the parts showing on substantially the same plane.

Figure 2 is a rear elevation slightly in perspective of the apron shown in Fig. 1, on a reduced scale, it being assembled as it would appear if on the form of the wearer.

I claim:

The ornamental design for an apron as shown and described.
